UNITED STATES PATENT OFFICE.

GUSTAV W. HEDSTROM, OF CHICAGO, ILLINOIS, ASSIGNEE OF ONE-HALF TO WENNER
W. FULFORD, OF CHICAGO, ILLINOIS.

DRYING MACHINE.

Application filed October 20, 1922. Serial No. 595,886.

To all whom it may concern:

Be it known that I, GUSTAV W. HEDSTROM, a citizen of the United States, and a resident of Chicago, in the county of Cook and State of Illinois, have invented certain new and useful Improvements in Drying Machines; and I do hereby declare that the following is a full, clear, and exact description thereof, reference being had to the accompanying drawings, and to the characters of reference marked thereon, which form a part of this specification.

This invention relates to improvements in drying machines for drying articles or films on articles as the latter pass slowly through the drying chamber of the machine, and is herein shown as designed more especially for drying the thin film of sealing medium, such as rubber compound, in the bottoms of the annular grooves of can ends, there placed for the purpose of sealing the joint between the can body and ends when the grooved rims of the ends are seamed over the body of the can. While my improvements are herein shown as adapted for drying sealing compound in the bottoms of can end grooves, it will be understood that the invention is not limited to this particular use, but may be adapted where analogous conditions for drying similar articles are found.

Sealing films have heretofore been applied to the grooves of can ends in a liquid or semi-liquid state and it is necessary, before applying the ends to the can bodies, to dry said films so that the films will not be scraped off the can end grooves before said ends are applied to the can bodies, or in the interval of time between which the can ends are so treated and the time when they are fixed or seamed to the can bodies, and it is also highly desirable that the drying of such films be carried on in such a way as to avoid uneven drying or blistering of the films on the faces of the can end grooves.

One of the objects of the present invention is to produce a machine for this purpose so constructed and arranged that the can ends, after the sealing medium has been applied thereto, may be caused to travel through a predetermined long path, ar-

ranged in a relatively short straight-way distance, and through an interval of time required to properly dry the applied sealing medium by the use of a very simple, compact and economical mechanism.

A further object of the invention is to decrease the dimensions of the machine, while increasing its capacity as compared to known machines, and to provide drying means which reduce to a minimum the artificial heat used for drying purposes.

Another object of the invention is to provide a simple and compact machine or device for this purpose which is so constructed and arranged as to handle a large number of can ends in a given time while providing ample duration of the drying period, and wherein the drying medium can be gently applied, so as to thereby avoid injuring the film by overheating it.

Another object of the invention is to provide a drying chamber wherein the can ends are caused to travel therethrough by the coaction of a lifting thread or threads which engages and supports the can ends, combined with means for causing the can ends to be driven or pass through the driving chamber when in engagement with said thread to cause the can ends to be positively driven through the drying chamber.

Another object of the invention, when applied to seal coated can ends, is to cause the can ends to rotate on their axes while moving over or along the thread so as to thereby bring all parts of the coatings or films uniformly under the influence of the drying medium.

Another object of the invention is to produce a drying machine having an annular drying chamber that is bounded by two (outer and inner) walls which bear the lifting thread or threads, with one adapted to be removed and replaced by a smaller or larger part to vary the radial dimensions of said chamber to receive different diameter can ends.

Further objects of the invention are to otherwise improve and simplify drying machines of this character, and the invention consists in the elements and combination of elements shown in the drawings and de-

scribed in the specification, and is pointed out in the appended claims.

In the drawings:

Figure 1 is a side view of a drying machine embodying my invention.

Figure 2 is a vertical partial section and partial elevation of the essential elements thereof.

Figure 3 is a plan view of the machine.

Figure 4 is a fragment illustrating a plurality of can ends showing their marginal grooves which receive the sealing medium.

Figure 5 is a fragmentary view similar to Figure 3, showing a modification of the can head advancing means.

Figure 6 is a fragmentary plan view of the drying chamber, showing a modification of the lifting thread.

A machine embodying my invention embodies in general terms a drying chamber formed between an outer and an inner member, one or both of which are formed with a spiral groove having closely spaced turns to constitute a lifting thread or threads which extends from end to end of the members, combined with means to cause the can ends to be driven through said chamber through relative movement of the can ends and the part or parts on which the lifting thread or threads are formed, the parts being so arranged that the drying medium can flow among the can ends thus driven through the drying chamber, there being means to feed the can ends to the entering end of the lifting thread or threads. When the drying chamber is flanked with one or two threads that are formed on fixed or non-rotative members, revoluble driving means may extend through the drying chamber to engage and drive the can ends while supported on the lifting thread or threads; but when the parts of said drying chamber walls which bear said lifting threads are rotative, the driving means that extend into and engage the can ends may be fixed relatively to said walls, and in either event the can ends are caused to travel through the driving chamber by relative angular movement of the threaded and driving means.

Referring now to the particular details of the illustrated embodiment of the invention, the same are made as follows:

10 designates an upright fixed shell which is formed on its inner cylindric wall with a continuous spiral groove extending from end to end thereof to constitute the turns 11, 12 of a spiral thread,—the lower turns of the thread being spaced more widely than the next succeeding threads in order to facilitate the placement of the can ends in the shell and engaged with the thread. 13 designates an inner fixed member shown as of exterior cylindric formation and disposed axially within the chamber 14 enclosed by said shell. The said member 13 is cut on its

outer circumference with a spiral groove to constitute a thread, the turns 15, 16 of which oppose the turns of the threads 11 and 12,—the turns of the thread at the lower end of the member 13 being spaced apart to correspond to the lower turns of the thread 12 at the lower end of the shell. The said shell 10 is open at its top. It is provided at one side near its bottom with a feed slot 17 through which can ends are fed into the chamber and into operative contact with the inner and outer threads of the shell 10 and member 13; the said can ends being delivered to said feed slot through a chute 18 which may be connected with the machine 75 for applying the sealing film to the can ends. The said can ends may be either manually or automatically fed into the drying chamber.

The said fixed inner member 13 and the shell 10 are of such relative size as to provide a drying chamber 14 of a width to receive the can ends with the margins thereof lying in overlapped relation to the threads on which they are delivered and by which they are caused to travel through rotation of the can ends on their axes. The annular drying chamber thus produced between the inner member 13 and the shell 10 is of a size to receive a plurality of stacks of can ends C, as illustrated in Figures 2 and 3, said stacks being spaced around the annular drying chamber at angular distances required to freely receive the driving means by which the can ends are caused to travel spirally about the drying chamber when supported on said threads and through said chamber from the receiving to the discharge end thereof.

The means shown in Figures 2 and 3 for driving said can ends thus delivered into the drying chamber with their edges supported at diametric points on the lifting threads comprise a plurality of driving rods 19 arranged within the annular drying chamber 110 and extending from end to end thereof, and located adjacent to the inner threaded member 13, with one of said rods engaging the rims of the can ends of each group or stack C inwardly beyond their centers, so that when the series of rods are revolved through the chamber the engagement of the rods will cause the can ends to be rotated on their axes and thus cause said ends to travel upwardly or outwardly along said threads. 120 Alternatively two of said driving rods 19' may be employed, as shown in Figure 5 and arranged to engage the can end edges both radially inside and outside of the end centers. When thus constructed and arranged revoluble movement of the rods 19' through the annular drying chamber has the effect to force the can ends over the lifting threads and advance them through the drying chamber without turning said ends on their cen- 130

ters. The use of the single driving rods, or equivalent means to cause the can ends to turn on their centers, is preferable, however, inasmuch as rotation of the can ends brings the coating or film uniformly into contact with the circulating drying medium, as will be evident.

Said driving rods are anchored at their lower ends in sockets formed on the upper face of a horizontal disc 20 which rests and rotates on a bed plate 21, and said disc 20 is provided with an axial bearing opening to receive the central upstanding bearing stud 22 that is fixed to or made integral with said plate 21. As herein shown, the inner fixed member 13 is attached to said upstanding stud by means of cap screws 23 which extend through openings in an annular inturned flange 24 of said inner member and engage screw-threaded openings in the upper end face of the bearing stud 22. The outer shell 10 is in a similar manner fixed to the bed plate 21 by means of cap screws 25 which extend upwardly through openings at the margin of said bed plate and are threaded into the thickened lower marginal portion 26 of the shell. Thus the outer internally threaded shell and the inner externally threaded member are rigidly fixed together in axial relation. With the construction described, it becomes practicable to remove one of the wall members (the shell 10 or member 13) and substitute a larger wall member, and thus vary the radial width of said drying chamber to adapt it to can ends of different diameters.

The said disc 20 may be rotated about the bearing stud 22 by any suitable means. As herein shown, it is provided with peripheral teeth 27, thus forming a large flat gear to which the driving rods are anchored. Said toothed disc is shown as driven by a pinion 28 fixed to the upper end of a shaft 29 that is mounted in a vertical bearing 30. Said shaft is driven in its bearing through the coaction of beveled gears 31 thereon and on a horizontal driving shaft 32 which is mounted in laterally spaced bearings 33 that are fixed to the top of the supporting standard 34 of the machine. Said supporting standard is provided at its upper end with a flanged head 35 which is fastened to the bed plate 21 through the medium of cap screws 36. The end of the drive shaft 32 remote from the beveled gears 31 is provided with a sprocket wheel 37 through which power may be applied to drive the shaft and through the gearing described the driving rod disc 21.

In order to effect accurate placement of the can ends in the chamber at the feed slot 17, I may provide a down-bearing spring 38 which extends through the feed slot and is fixed to the shell 10 by a screw 39. Auxiliary to said spring, I may also provide

opposite to said spring a guide lug 40 which is attached to the central fixed member 13 parallel with but slightly above the bottom of the receiving thread, as by means of the screw shown in Figure 2.

With the construction described it will be noted that all of the can ends are delivered to the drying chamber through a single feed slot 17 and that the driving posts 19 are spaced at sufficient angular distances apart to permit the can ends to be readily fed into the chamber at a time when the space between two adjoining driving rods is opposite the feed slot. The series of driving rods and the geared or toothed disc 20 are adapted to be rotated at a relatively slow speed so that with the proper number of turns of the inner and outer threads the can ends will be moved uniformly and slowly through the drying chamber; and by reason of this relatively slow movement ample time is given to feed the can ends into the chamber between said driving posts and to properly engage the diametric margins thereof with the lifting threads.

The down-bearing spring 38 serves to hold each can end as it is delivered to the chamber firmly on a raised annular face 41, as shown in Figure 2, substantially flush with the bottom or lowermost operative threads, and the guide lug 40 serves to accurately guide the far margin of the can end into the lower thread of the fixed member 13.

42, 42 designate air inlets which communicate with the bottom of the drying chamber to deliver air to the chamber, said inlets being formed in openings in the bed plate 21 and geared disc 20, as the openings in said geared disc 20 are brought in line with the openings in the fixed bed plate 21, as shown in full lines in Figure 2 and in dotted lines in Figure 3. If desired, the air passing upwardly through said inlets 42 to the drying chamber may be heated by an annular heating ring 43 disposed coaxially with respect to the drying chamber and overlapping said inlets. Said heating ring may be heated by steam passing therethrough, or may constitute a slotted gas burner and, in either event, the heating medium is supplied to the ring by a pipe or conduit 44, as shown in Figure 1. Said heating ring is supported on the bed plate by means of hangers 45.

In the operation of the device the can ends are fed to the drying chamber through the feed slot 17 into engagement with the lowermost operative widely spaced threads and the geared disc 20 is slowly rotated through the driving connection described to cause the driving rods 19 to bear on or impinge against the margins of the can ends adjacent to the inner thread. This engagement of the annular series of moving

rods with the can ends causes said ends to rotate on their axes or to be bodily forced ahead of the rods, depending upon the use of a single or pair of driving rods (19, 19') and, through co-operation of the margins of the ends with the lifting threads, said can ends are gradually lifted from the receiving to the discharge end of the drying chamber.

10 Said threads terminate just short of the upper ends of the shell and central member 13 to provide non-threaded annular faces 46, 47, respectively, whereby the margins of the ends are released from the action 15 of the threads and the ends are caused to be moved upwardly, as the can ends below travel through the drying chamber in groups, lying one flat on the other, as indicated at the upper end of Figure 2. In 20 order to confine the groups of can ends after they have been raised above the lifting threads, I may provide a cylindric guard 48 made of sheet metal and fastened at its lower flanged end by screws 49 to the 25 upper end of the shell, as shown in Figures 1 and 2. The inner face of said guard 48 is an extension of the plain inner face 46 of the shell at the upper end thereof, so that the groups of free can ends are raised in 30 stacked relation upwardly through the guard,—this relation being maintained by the extension of the driving rods 19. The contact of the driving rods with the margins of the superposed groups of can ends at the 35 discharge end of the drying chamber will not be sufficient to turn the weight of said groups so that said groups will non-rotatively rise to the upper open end of the guard. The said guard is provided opposite the stacks with vertical grooves 50 through which the thumb and a finger may be inserted to lift the upper can ends from the stacks.

40 In Figure 4 is fragmentarily shown a plurality of can ends C grouped in the relation shown at the upper ends of the stacks, and in said figure, 51 designates the film of sealing medium which was applied to the bottoms of the grooves of the can ends, and 55 which medium has been dried and hardened during the passage of the can ends through the drying chamber.

55 From what has been said, it will be observed that a relatively small diameter and compact drying chambers, equipped with the lifting threads, as shown, is capable of continuously handling and passing through the drying chamber a large number of can ends, and it will furthermore be observed 60 that the effective length of travel of the can ends through the chamber is large, as compared to the height or length of the drying chamber. This construction enables a 65 large number of can ends to be passed slowly through the drying chamber, while

permitting a large number of can ends to be handled in a given machine of small dimensions.

In Figure 6 is shown a modification wherein but a single spiral lifting thread 70 11' is employed. It is supported on the outer cylinder 10' and extends inwardly beyond the centers of the can ends to constitute a shelf-like support for the can ends. The outer surface of the inner cylindric 75 member 13' is in this instance smooth for engagement with the edges of the said ends, which are caused to rotate on their axes by engagement of the driving rods 19' with the can end edges between the inner edge of the 80 shelf-like thread 11' and the inner member 13'. The same general principle of causing the can ends to travel through the drying chamber may be effected, though in a less efficient manner, through a reversal of the 85 construction described wherein the inner and outer thread carrying members may be made to rotate and to coact with fixed or non-revolvable can end driving rods. In the last suggested construction, it will be preferable to provide a plurality of angularly spaced feed slots 17.

90 It is to be understood that the principles of the invention may be employed in machines differing in structural detail from the 95 construction herein shown within the spirit and scope of the appended claims, without sacrificing the utilities and advantages referred to, and that it is the intent to claim all of inherent novelty shown in the drawings and described in the specification.

100 I claim:

1. A drying machine for the purpose set forth comprising a drying chamber with 105 means for admitting can ends thereto, and combined lifting threads and can end driving means to cause the can ends to travel through said chamber.

110 2. A drying machine for the purpose set forth comprising a drying chamber with means for admitting can ends thereto, combined lifting threads and can end driving means to cause the can ends to travel through said chamber, and means to afford circulation of a drying medium through said chamber.

115 3. A drying machine for the purpose set forth comprising a drying chamber with means for admitting can ends thereto to be arranged in parallel groups with the groups 120 angularly spaced about the chamber, and combined lifting threads and can end driving means to engage the can ends.

125 4. A drying machine for the purpose set forth comprising outer and inner spiral lift threads forming between them a drying chamber, means to feed can ends into contact with the entering ends of said threads, and driving means to engage said can ends when engaged with said threads.

5. A drying machine for the purpose set forth comprising outer and inner spiral lift threads forming between them a drying chamber, means to feed can ends into contact with the entering ends of said threads, and means to rotate said can ends on their axes. 70

6. A drying machine for the purpose set forth comprising a drying chamber bounded by inner and outer walls on which are formed coacting closely spaced lifting threads adapted to be engaged by the can end margins, and means to drive said can ends while engaged with said threads. 75

7. A drying machine for the purpose set forth comprising a drying chamber bounded by inner and outer walls on which are formed coacting closely spaced lifting threads adapted to be engaged by the can end margins, can end driving means extending through said chamber for engagement with the can end edges, and feed means at one side of the drying chamber co-operating with the can head driving means to group the can ends in said chamber in angularly spaced, outwardly moving groups. 80

8. A drying machine for the purpose set forth comprising a drying chamber bounded by inner and outer walls on which are formed lifting threads adapted to be engaged by the can end margins, and means revoluble through the annular chamber to engage the margins of the can ends to drive said can ends while engaged with said threads. 85

9. A drying machine for the purpose set forth comprising a drying chamber bounded by inner and outer walls, co-operating lifting threads on said walls adapted to be engaged by the margins of can ends, and revoluble driving rods extending through said chamber to engage the margins of the can ends to exert eccentric driving force thereon to rotate said ends. 95

10. A drying machine for the purpose set forth comprising a drying chamber bounded by inner and outer walls, lifting threads at the side of the chamber adapted to support the can ends, a feed slot at one end of said chamber through which can ends are delivered to engage said threads, and means to rotate the can ends on their axes while resting on said lifting threads. 100

11. A drying machine for the purpose set forth comprising a drying chamber bounded by inner and outer walls, co-operating lifting threads on said walls adapted to be engaged by the margins of can ends, a can end feed slot at one end of said chamber, and means to drive said can ends when resting on said threads, the threads adjacent to said slot being widely spaced to readily receive the can ends and the remaining threads being closely spaced. 110

12. A drying machine for the purpose set forth comprising a drying chamber bounded by inner and outer walls, lifting threads at 115

the sides of the chamber adapted to support the can ends, a can head feed slot at one end of said chamber, means to drive the can ends when supported on said threads, and guide means opposite to said slot to 70 guide the can ends into engagement with said threads. 120

13. A drying machine comprising a shell having an inner spiral thread, an inner member having an external spiral thread to form 75 between them a drying chamber, means to feed can ends into one end of said chamber to be supported on said threads, means to drive said can ends when supported on said threads, and means to support the thread bearing members whereby one of said members may be substituted by another of different dimension to vary the width of said drying chamber. 80

14. A drying machine comprising a cylindric shell having an inner spiral thread, an inner concentric member having an external spiral thread to form therebetween an annular drying chamber, a fixed bed plate supporting said shell and inner member, and a rotative disc mounted on said plate and provided with a plurality of can end driving rods which extend through said annular chamber. 85

15. A drying machine comprising an annular shell having an inner spiral thread and a feed opening, an inner concentric member having an external spiral thread to co-operate with that of said shell, a fixed bed plate supporting said shell and inner member, a rotative disc supported on said plate and provided with a plurality of driving rods which extend through said chamber for driving engagement with can ends, 95 and means to rotate said disc. 100

16. A drying machine comprising an annular shell having an inner spiral thread and a feed opening, an inner concentric member having an external spiral thread to co-operate with that of said shell, and a fixed bed plate supporting said shell and inner member, by means permitting one of the thread bearing members to be removed and another substituted therefor to adapt 110 said annular drying chamber to can ends of different diameters. 115

17. A drying machine comprising a drying chamber flanked by closely spaced spiral lifting threads to support can ends, means 120 to cause the can ends to travel through said chamber when supported on said threads, and a guard fixed to and extending above the outer wall of said chamber and having a plain inner face. 125

18. A drying machine comprising a drying chamber flanked by closely spaced spiral lifting threads to support can ends, means 130 to cause the can ends to travel through said chamber when supported on said threads, and a guard fixed to and extending above

the outer wall of said chamber and having a plain inner face, said guard being provided with a plurality of angularly spaced slots opening through the outer end edge 5 of the guard.

19. A drying machine for the purpose set forth comprising a fixed bed plate provided with an upstanding bearing stud, a shell supported on said plate, a member enclosed 10 by and concentric with said shell, said shell and member being provided with co-ope-

tive spiral can end supporting and lifting threads, a geared disc rotatively mounted on said stud and having means to rotate it, and driving means fixed to said disc and extending through said annular chamber for contact with said can ends. 15

In witness whereof I claim the foregoing as my invention, I hereunto append my signature this 14th day of October, A. D., 20 1922.

GUSTAV W. HEDSTROM.
